WINDOW CONSTRUCTION

Oliver M. Edwards, Syracuse, N. Y., assignor to
 The O. M. Edwards Company Inc., Syracuse,
 N. Y., a corporation of New York

Application March 17, 1937, Serial No. 131,428

6 Claims. (Cl. 189—64)

This invention relates to window constructions, particularly to windows for use in motor vehicles, railway cars, airships, etc.

It has for its object a window construction in which the glass pane is cushioned throughout its entire circumference against strains, shocks and jars and to internal strains due to expansion and contraction under varied degrees of temperature.

It further has for its object a window construction in which the resilient mounting or resilient sash frame for the glass pane is clamped or compressed on the margins of the glass pane, so that the resilient mounting or sash frame not only cushions the glass pane throughout its entire circumference against strains, shocks, etc., but also resiliently but snugly holds the glass in the mounting of the glass frame.

It further has for its object a window construction in which the mounting or sash frame in its entirety is an elastic and compressible or resilient tirelike member having a groove for receiving the margin of the glass pane, with the greater part of said member located beyond the edge of the glass pane and the mounting located 25 in a channel in an outside holding means or frame, which channel has means operable to compress the mounting against the walls of the channel and against opposite sides of the margin of the glass pane.

It further has for its object an elastic and compressible or resilient mounting for the glass pane which is under tension when applied to the glass pane and also under compression, when the sash, including the glass pane and its mounting, 35 is mounted in the channel on an outside or holding frame.

It further has for its object a double sash, each including a compressible mounting or sash frame directly receiving the margin of the glass pane 40 and coacting directly with the walls of the channel of the supporting or outside frame, the double sash being so mounted in the channel that when compressed in the channel, the mountings of each compresses against each other and also 45 against the sides and bottom of the channel.

It further has for its object means compressible between the mountings of the two sashes for dehydrating the air between the sashes.

The invention consists in the novel features and in the combinations and constructions hereinafter set forth and claimed.

In describing this invention, reference is had to the accompanying drawing in which like characters designate corresponding parts in all the views.

Figure 1 is a fragmentary elevation of a double sash window embodying this invention.

Figure 2 is a sectional view on line 2—2, Figure 3.

Figure 3 is a fragmentary sectional view on line 3—3, Figure 1.

Figure 4 is an elevation on a reduced scale illustrating the continuity of the elastic and compressible mounting or sash frame.

Figure 5 is a view similar to Figure 2 illustrating a single sash window embodying this invention.

The window is designed to be fixedly mounted, that is, to have no opening and closing movement.

1 designates the glass pane and 2 the mounting for the glass pane which may be considered a sash frame, as distinguished from a rubber channel, serving as a seat for the margin of the glass pane, and mounted in the channel of a 20 sash frame of wood or metal, which in turn is mounted in a window frame.

3 designates the outside or window frame formed with a channel 4 for receiving the mounting or mountings 2, the window frame having 25 one side 5 of the channel removable and operable to have a clamping or compressing action against the mounting or mountings 2.

The mounting 2 is a tirelike member, which entirely surrounds the periphery of the glass 30 pane 1 and is provided with a groove 6 for receiving the margin of the glass pane, the greater part 7 of the mounting being located beyond the edge of the glass pane 1. The mounting is elastic and compressible, and usually of rubber or some 35 form of sponge rubber. It is in the form of an endless belt and initially is of less length circumferentially than the edge of the glass pane 1, so that it is stretched when placed on the glass pane, and hence, under tension, when in position on the glass pane. Preferably, the glass pane has rounding corners, as seen in Figure 1, and consequently the elastic compressible mounting 2 is rounding at the corners, and likewise the channel 4 of the outside frame 3 is rounding. 45

This outside frame is usually the window frame set directly into the window opening of the body of the vehicle or other structure to which the window is applied. The frame 3 is formed of metal and the channel is here shown as substantially rectangular in general form in cross section with one side 5 thereof removable and clamped in position, as by screws 8. Also, the cross sectional shape of the member 2 is different from that of the channel, and in order to 55

5 permit distortion of the member 2, when compressed, and during such distortion to press against the sides and bottom of the channel, and in a double sash, also against the mounting of the other glass pane.

5 As here illustrated, the outer corners of the members 2 instead of being square are removed, so that the outer periphery of the member 2 is semi-octagonal.

10 In Figure 2, wherein a double sash is shown, the bottom of the channel is formed with a rib 9, which extends part way between the bodies 2 of the double sash and serves as a shoulder for preventing unintentional displacement of the sash, the rubber mounting 2 of which is located against the fixed side of the channel 4, that is, the side opposed to the removable side 5. In placing the sash with its mounting 2 in the channel against the fixed side of the channel, the mounting 2 is 15 compressed at some points sufficiently to let the mounting snap in the channel over the rib 9 and in removing this sash, the mounting is likewise compressed sufficiently to permit it to snap over the rib 9. This rib 9 is merely high enough to prevent unintentional displacement of the sash adjacent the fixed side of the channel 4, when the other sash, which is adjacent the removable side 5, is demounted.

30 In the construction shown in Figure 2, when the removable side 5 of the outside frame 3 is clamped by means of the screws 8, the mountings 2 of the double sash are compressed against each other and toward the fixed side of the channel 4 and the removable side 5 compressed against the adjacent 35 mounting 2. This compression force also compresses the sides of the grooves of the mountings on the margins of the glass panes 1.

40 In the form shown in Figure 5, the channel 40 of the outside frame 30 is formed with a rib or lip 90 on the side thereof adjacent the removable side 50, corresponding to the rib 9 of Figure 2, to prevent inadvertent displacement of the single sash.

45 The means for dehydrating the air in the space between the two glass panes 1, which space is sealed by the mountings 2, compressed against each other, consists of a flattened tube 10 extending between the mountings 2 and opening at one end into said space and at its other end into a chamber 11 in which a moisture absorbing material is located, this being usually what is known as activated alumina. The chamber has a detachable cap or plug 12 opening through the face of the outside frame 3. The cap permits the moisture absorbing material, which is usually in the form of a plug or cartridge, to be removed and replaced. These chambers 11 and tubes 10 are preferably located at one or more corners of the sash. The tube 10 extends between the mountings 2 at the rounding corners.

60 As the window openings in the body are usually rectangular, the outside window frame 3 is rectangular and the exterior corners square, and for convenience, the chambers 11 are located in the square portions of the outside frame beyond the 65 rounding corners of the bottom of the channel 4 of the outside or window frame 3. When the mountings 2 are compressed against each other by the clamping action of the movable side 5 of the channel 4, the mountings 2 distort to conform 70 to the contour of the flattened tube 10 and snugly fit around the flattened tube 10.

75 A sash either single or double of this construction is extremely economical to manufacture, readily placed into position and demounted, and the glass panes resiliently mounted and amply

protected against shocks and strains. Owing to the resilient frame of rubber, no sash frame of wood or metal is necessary, and hence a glass pane of maximum area may be installed in a window opening of a given size.

5 What I claim is:

10 1. In a window construction, a sash including a glass pane and a surrounding marginal tirelike frame of elastic and compressible material, said frame being formed with a groove for receiving the margin of the glass pane, the frame being located for the most part beyond the edge of the glass pane, and a circumferential outside frame formed with a channel for receiving the tirelike frame, the outside frame including means for 15 compressing the tirelike frame in the channel and against the margin of the glass pane, the portion of the tirelike frame in the channel being of different cross sectional outline from the channel, whereby it distorts, when compressed, in the 20 channel.

2. In a window construction, a double sash, each including a glass pane and a surrounding marginal tirelike frame of elastic and compressible material, each tirelike frame being formed 25 with a groove for receiving the margin of the companion glass pane and the tirelike frame being located for the most part beyond the edge of the glass pane, and a circumferential outside frame formed with a channel for receiving the tirelike 30 frames with the tirelike frames abutting against each other, the outside frame including means for compressing the tirelike frames in the channel and against each other and compressing the walls of the groove of each tirelike frame against the 35 margins of the glass panes, the bottom of the channel of the outside frame being formed with a rib extending partway between the tirelike frames.

3. In a window construction, a double sash, each including a glass pane and a surrounding marginal tirelike frame of elastic and compressible material, the tirelike frames of the sashes being 40 separate from each other, each tirelike frame being formed with a groove for receiving the margin of the companion glass pane, each tirelike 45 frame being located for the most part beyond the edge of its glass pane, and a circumferential outside frame formed with a channel for receiving the tirelike frames with the tirelike frames abutting at their opposing sides against each other, the 50 outside frame including means for compressing the walls of the groove of each tirelike frame against the margins of its glass pane, the tirelike frames together having a cross sectional shape different from that of the channel for permitting 55 slight distortion thereof during the compressing of said frames in the channel and against each other.

4. In a window construction, a double sash, each including a glass pane and a surrounding marginal tirelike frame of elastic and compressible 60 material, each tirelike frame being formed with a groove for receiving the margin of the companion glass pane, each tirelike frame being located for the most part beyond the edge of its glass pane, and a circumferential outside frame formed with 65 a channel for receiving the tirelike frames with the tirelike frames abutting against each other, the outside frame including means for compressing the walls of the groove of each tirelike frame against the margin of its glass pane, the tirelike 70 frames together having a cross sectional shape different from that of the channel for permitting slight distortion thereof during the compressing of said frames in the channel and against each other, and the bottom of the channel being formed 75

with a rib extending part way between the tirelike frames.

5. In a window construction, a double sash, each including a glass pane and a surrounding marginal tirelike frame of elastic and compressible material, each tirelike frame being formed with a groove for receiving the margin of the companion glass pane, each tirelike frame being located for the most part beyond the edge of its glass pane, and a circumferential outside frame formed with a channel for receiving the tirelike frames with the tirelike frames abutting at their opposing sides against each other, the outside frame including means for compressing the tirelike frames in the channel and against each other and compressing the walls of the groove of each tirelike frame against the margin of its glass pane, and means for dehydrating the air between the glass panes including a flattened tube extending between the tirelike frames and against which said frames are compressed.

6. In a window construction, a double sash,

each including a glass pane and a surrounding marginal tirelike frame of elastic and compressible material, each tirelike frame being formed with a groove for receiving the margin of the companion glass pane, each tirelike frame being located for the most part beyond the edge of its glass pane, and a circumferential outside frame formed with a channel for receiving the tirelike frames with the tirelike frames abutting at their opposing sides against each other, the outside frame including means for compressing the tirelike frames in the channel and against each other and compressing the walls of the groove of each tirelike frame against the margin of its glass pane, and means for dehydrating the air between the glass panes including a chamber for receiving a moisture absorbing material, located in the outside frame, and a tube extending from the chamber between the tirelike frames and against which the tirelike frames are compressed.
